UNITED STATES PATENT OFFICE.

JOHN R. STARK, OF NASHVILLE, TENNESSEE, ASSIGNEE TO OWENS-STARK MANUFACTURING COMPANY, OF NASHVILLE, TENNESSEE.

ADJUSTABLE BED.

1,343,593.

Specification of Letters Patent. Patented June 15, 1920.

Application filed June 14, 1919. Serial No. 304,320.

To all whom it may concern:

Be it known that I, JOHN R. STARK, a citizen of the United States, residing at Nashville, in the county of Davidson and State of Tennessee, have invented certain new and useful Improvements in Adjustable Beds, of which the following is a specification.

This invention relates to adjustable beds and has for its object the provision of simple and efficient means whereby the sections of the bed may be easily raised and lowered and effectually held in the position to which they may be adjusted. The invention relates particularly to adjustable beds of that type in which the bed bottom comprises head, foot and seat sections which may be pivotally adjusted relative to each other and provides means whereby the foot and seat sections may be locked together so as to extend in a single plane or the foot section may be permitted to swing pivotally about the end of the seat section and depend below the normal plane of the bed bottom.

The invention is illustrated in the accompanying drawings, in which—

Figure 1 is a side elevation of a bed embodying my improvements and showing the several sections of the bed bottom arranged in a horizontal plane to permit the use of the bed for sleeping;

Fig. 2 is a similar view showing the several sections adjusted to permit the occupant to assume a somewhat reclined position with the knees bent and raised;

Fig. 3 is a transverse section on the line 3—3 of Fig. 1;

Fig. 4 is an enlarged detail view of the raising and lowering means;

Fig. 5 is a similar view of one member of the housing;

Fig. 6 is a transverse section of said mechanism;

Fig. 7 is a detail perspective view of a portion of one of the side bars of the bedstead frame.

In carrying out my invention, I employ a bedstead comprising a head section 1, a foot section 2 and side bars 3 connected and secured to said head and foot sections in any well-known manner. The side bars 3 are preferably constructed of angle-iron, as shown most clearly in Fig. 7, and near their rear or foot ends the inwardly projecting webs of the side bars are cut away, as shown at 4. The gap thus produced in the side bars

is normally filled by the horizontal inwardly projecting web 5 of a track member which is pivoted at 6 to the side bar and consists of the said horizontal web 5 and a vertical web 7 fitting up against the outer face of the side bar. A wing screw or similar securing device 8 is carried by the forward free end of the said track member and is adapted to directly engage the horizontal web of the side bar at the forward end of the gap 4 so as to secure the track member normally in raised position.

The bed bottom comprises a head section 9, a seat section 10 and a foot section 11, the sections 9 and 10 being pivotally joined, as indicated at 12, and the sections 10 and 11 being similarly pivotally joined, as shown at 13, the pivot members in both instances being connected by an inverted transverse arched member 14 whereby the side members of the several sections will be properly braced. The sections 9, 10 and 11 each consists of side angle bars 15 and a woven spring fabric 16 secured to and stretched between the said side bars. The foot end of the foot section 11 is free and is equipped with rollers (not shown) adapted to run upon the horizontal webs of the side bars and the track members 5 so that if the said track members be in their normal position, as shown in the drawings, and the seat section 10 be swung upwardly, as indicated in Fig. 2, about its pivotal connection with the head section 9, the foot section will assume an angular position relative to the seat section and its free foot extremity will be supported by the side bars 3. If it be desired to permit the occupant of the bed to sit up or it is desired to permit the occupant's feet to assume a more pendent position the holding device 8 is released whereupon the track member will swing downwardly, as indicated by dotted lines in Fig. 2, and the foot section 11 may then depend through the cut-away portions 4 of the side bars. It is to be noted that the pivot member 12 which connects the sections 9 and 10 also serves to connect the said sections to the side bars of the bedstead frame so that displacement of said sections longitudinally of the bedstead frame cannot occur although they may be adjusted pivotally, as indicated in Fig. 2.

It is sometimes desirable to permit a patient to raise his feet without bending the knee, and, in this event, a latch 17, pivotally

mounted upon the foot section is engaged over a stud 18 on the seat section so that said sections will be locked in alinement.

To raise or lower the sections and adjust the bed to the comfort of the patient or the convenience of attendants, I provide operating mechanism arranged to act upon the head and seat sections and each comprising a rack 19 pivoted at its upper end to the respective section and depending freely therefrom through a casing 20 consisting of mating members 21 and 22. The members 21 and 22 are provided with transverse openings and on their inner faces, around said openings, are opposed bosses 23 which serve to provide extended bearings for a securing bolt 24 whereby the two sections may be secured together. Each casing member comprises a side web 25 and edge flanges 26 on their inner faces which are adapted to abut, as shown in Fig. 6. The casing members are substantially triangular in form, one side of the triangle being arcuate so as to accommodate the parts while economizing in material, and the flanges on the straight sides of the triangle or edges of the casing are cut-away to provide slots 27 through which the respective rack bars 19 may play. One of the casing members is provided at its upper straight edge on its outer side with lateral lugs or flanges 28 which are adapted to fit against the under side of the side bar of the bedstead frame and receive fastening bolts or screws whereby the casing will be firmly secured in position. Each of the casing members is provided with an opening 29 through which a shaft 30 may extend and upon the inner side of one casing member is a boss or projection 31 which constitutes a hub bearing for the said shaft. The shaft 30 extends entirely across the bed and has angular ends, as shown at 32, whereby it may be engaged by an operating crank or other form of turning tool 33. A pinion 34 is secured upon the shaft 30 between the casing members 21 and 22 and is held in the central vertical plane of the casing by the boss or projection 31 and a coacting boss or projection 35, as clearly shown in Fig. 6. This pinion meshes directly with the rack bar 19, as shown clearly in Fig. 4, and rotation of the pinion will effect movement of the rack bar as will be readily understood. The rack bar being pivoted at one end to the side of the section which is to be adjusted, it will assume different angular positions within the casing and this movement of the rack bar is accommodated by the slots 27, a roller 36 being carried by a pin or stud 37 in the upper angle or point of the casing to bear upon the straight smooth edge of the rack bar and thereby hold it in engagement with the pinion 34 in all of its various angular positions. To lock the section in a set position, 60 I employ a dog 38 which is pivotally mount-

ed within the casing and is equipped with a tooth 39 adapted to engage between two adjacent teeth of the pinion 34. The pivot 40 of this dog is threaded into the same or otherwise secured thereto and extends transversely through one casing member, while its extremity is journaled in a socket in the other casing member, as indicated at 41. The outer portion of the pivot or pin 40 is bent to provide a crank or handle 42 whereby the pin may be rocked and the dog consequently thrown into or out of engagement with the pinion. A leaf spring 43 is secured at one end within the casing and its free end engages a notch 44 in the dog, the relative positions of the several parts and the shape of the spring being such that the spring will be under tension whether the dog be in or out of engagement with the pinion and will tend to hold the dog in the position in which it has been set. Upon reference to Fig. 5, it will be noted that the boss or projection 31 has two plane faces 45 to permit the rack bar 19 to clear the boss in the event that it should move laterally when conforming to the adjustment of the parts.

It is thought the operation of the device will be readily understood from what has been said, taken in connection with the accompanying drawings, but it may be noted that when it is desired to raise a section of the bed bottom as, for instance, the head section 9, the handle member 42 is swung in the proper direction to release the dog 38 from its engagement with the pinion 34, after which the shaft 30 is rotated so that the pinion 34 will act upon the rack 19 to move the same upwardly and thereby raise the head section. When the section has been raised to the desired position, the dog is thrown into engagement with the pinion and will effectually prevent retrograde movement of the rack bar and the section to which it is attached. It will be readily seen that my improved mechanism is exceedingly simple, compact and inexpensive. It will operate directly upon the section to be adjusted and does not require laborious strain in order to operate effectively and by its use the section which may be raised will be firmly supported in the raised position without the use of complicated, cumbersome and expensive interlocking devices which ordinarily interfere with the free movement of nurses or other attendants in the vicinity of the bed.

Having thus described the invention, what is claimed as new is:

1. In an adjustable bed, the combination of a supporting frame having parts of its side bars cut-away, track members pivotally attached to said side bars at their rear ends and provided at their front ends with means for detachably and directly engaging the side bars and locking the track members in

position to fill the cut-away portions of said side bars, a seat section pivotally attached to the frame, and a foot section pivotally connected with the seat section and having 5 one end free and arranged to ride upon the side bars of the frame and the said track members.

2. In an adjustable bed, the combination of a frame, a bed bottom section pivotally 10 connected with the frame, a casing secured to and depending from the frame, said casing consisting of mating members secured together having two straight converging edges and having axially alined central 15 openings and provided with elongated registering notches in their top edges and in the straight edges converging to the top edges, a shaft rotatably mounted in the central openings of said members, a pinion on said 20 shaft within the casing, a rack bar pivoted

to the bed bottom section and depending therefrom through the notches in the casing members and meshing with said pinion, a roller mounted in the angle formed by the converging edges of the casing in fixed relation to the casing and the pinion and bearing upon the rack bar in all angular positions of the rack bar to hold it in mesh with the pinion, a dog mounted in the casing below the pinion to engage the same, a 30 spring secured in the casing and disposed approximately on a radius of the pivot of the dog with its free end engaging the dog whereby to hold it either in or out of engagement with the pinion, and means extending exteriorly of the casing for moving the dog into or out of engagement with the pinion. 35

In testimony whereof I affix my signature.

JOHN R. STARK. [L. S.]
